[57] CLAIM

The ornamental design of a maple leaf sun visor, as
shown and described.

DESCRIPTION

FIG. 1 is a top plan view of a maple leaf sun visor showing
my new design;

FIG. 2 is a bottom plan view thereof;

FIG. 3 is a front elevational view thereof;

FIG. 4 is a rear elevational view thereof; and,

FIG. 5 is a side elevation view thereof, the other side
being a mirror image thereof.

FIG. 1

FIG. 2

FIG. 3

FIG. 4

FIG. 5
